UNITED STATES PATENT OFFICE.

CHARLES McL. MOSS, OF PITTSBURGH, AND ROY J. WENSLEY, OF EDGEWOOD PARK, PENNSYLVANIA, ASSIGNORS TO WESTINGHOUSE ELECTRIC AND MANUFACTURING COMPANY, A CORPORATION OF PENNSYLVANIA.

AUTOMATIC SUBSTATION.

Application filed July 10, 1918, Serial No. 244,233. Renewed September 18, 1923.

To all whom it may concern:

Be it known that we, CHARLES McL. Moss, a citizen of the United States, and a resident of Pittsburgh, in the county of Allegheny and State of Pennsylvania, and Roy J. WENSLEY, a citizen of the United States, and a resident of Edgewood Park, in the county of Allegheny and State of Pennsylvania, have invented a new and useful Improvement in Automatic Substations, of which the following is a specification.

Our invention relates to automatic substations and particularly to means for controlling the operation of automatic substations for electric-railway systems.

One object of our invention is to provide means responsive to the position of the load on the railway system for automatically starting the converting devices of the substation.

Another object of our invention is to provide a Wheatstone-bridge device for controlling the operation of a converting device.

A further object of our invention is to provide a controlling device, of the above indicated character, that shall be simple and inexpensive to construct and effective in its operation.

In practicing our invention, we provide an electric-railway trolley circuit the impedance of portions of which constitutes one arm of a Wheatstone bridge. The unbalancing of the bridge is adapted to control the operation of a converting device. Since the position of an electric locomotive with respect to the trolley circuit determines the impedance of the circuit, the device may be adapted to be so responsive that the converting device may be started only when the locomotive is in the zone or section that is to be supplied with energy from the substation.

The single figure of the accompanying drawing is a diagrammatic view of an electric-railway trolley circuit embodying our invention.

A direct-current trolley circuit 1 is adapted to be supplied with energy from an alternating-current source 2 of energy through substations 3 and 26. That is, the converting device 4 of the substation 3 is adapted to be so controlled by a Wheatstone bridge 6 that it is automatically started and connected between the source 2 of energy and the circuit 1 when a locomotive 5 enters the

section of the circuit 1 that is to be supplied with energy from the substation 3. In other words, the station 3 is operated when a car is between a reactor 14 and a reactor 27 and the station 26 is operative when a car is between the reactor 28 and the reactor 14.

The Wheatstone bridge 6 comprises two resistors 7 and 8, a reactor 9, a relay 10, and a transformer 11 for operatively connecting the bridge to the source 2 of alternating-current electromotive force. The resistors 7 and 8 and the reactor 9 constitute three arms of the bridge, the fourth arm of which is the impedance between the points 12 and 13 of the circuit 1. In other words, the position of the locomotive 5, with respect to the points 12 and 13, determines the impedance of one arm of the bridge 6. In order to ensure correct operation of the bridge, a reactor 14 is connected in the circuit 1 and the bridge is supplied with voltage from an alternating-current source of electromotive force. Also, in order that the operation of the device shall not be impaired by reason of the circulation of direct current from the circuit 1, a condenser 25 is connected in circuit with the reactor 9. The relay 10 is connected across the points 15 and 16 of the bridge, and its contact members 17 constitute the separable terminals of a circuit 18 comprising an actuating electromagnet 19 and a source 20 of electromotive force. Reactors may be substituted for the resistors 7 and 8 without affecting the operation of the bridge.

The converting device 4 comprises an alternating-current motor 21 that is directly connected to a direct-current generator 22. The motor 21 is connected, through a circuit-interrupter 23 and a transformer 24, to the main generator 2, and the generator 22 is connected to the circuit 1. The electromagnet 19 is adapted to actuate the circuit-interrupter 23 to thereby connect the motor 21 to the generator 2, under predetermined conditions.

The Wheatstone bridge 6 is so arranged that, when the impedance across the points 12 and 13 is reduced to a predetermined value by reason of the locomotive 5 being between the reactors 14 and 27, the contact members 17 of the relay 10 will be engaged. When the contact members 17 are engaged, the electromagnet 19 will operate to operatively connect the motor 21 to the generator

2 and thus cause the generator 22 to supply energy to the circuit 1. When the locomotive 5 moves to a remote position, as shown between the reactors 14 and 28, it is supplied 10 with energy from the substation 26. The impedance between the points 12 and 13 will be so increased that the contact members 17 will be disengaged and thereby permit the circuit-interrupter 23 to be opened 15 and the motor 21 to be disconnected from the generator 2. With our invention, the substation 3 may be caused to respond promptly to the demand for energy on the circuit 1 between the reactors 14 and 27, irrespective of the voltage of the circuit.

The reactors 14, 27 and 28 are of such relatively high reactance that the respective bridges are unbalanced when the locomotive is outside the section connected to the respective bridges. The bridges are balanced during the time when the locomotive is in the sections connected thereto and thus the relays 10 which are so adjusted that their contact members are engaged when 25 the bridges are balanced so energize the operating electromagnets 19 as to close the interrupters. The station 26 is provided with a motor generator set and with a bridge 6 similar to that of station 3. 30 It will be understood that the motor 21 may be started by the use of any of the means well known in automatic substations and the generator 22 may be similarly controlled without departing from the spirit 35 and scope of the invention, as set forth in the appended claims.

We claim as our invention:—

1. In an electrical system, the combination with a main circuit, a direct-current trolley circuit and a transforming device, of means responsive to the impedance of the trolley circuit for operatively connecting the transforming device between the main and the trolley circuits.

2. In an electrical system, the combination with a main circuit, a direct-current distributing circuit and a converting device, of means responsive to a change in impedance in the distributing circuit for operatively connecting the converting device between the said circuits.

3. In an electrical system, the combination with an alternating-current main circuit, a direct-current load circuit and a converting device, of means responsive to the change in resistance of the direct-current circuit for operatively connecting the converting device between the said circuits.

4. In an electrical system, the combination with an alternating-current main circuit, a direct-current load circuit and a converting device, of a Wheatstone bridge, the resistance of portions of the load circuit constituting one arm of the bridge, and means whereby the bridge controls the con-

nnection of the converting device to the circuits.

5. In an electrical system, the combination with an alternating-current main circuit, a direct-current load circuit and a converting device, of a Wheatstone bridge, the resistance of the load circuit constituting one arm of the bridge, and means dependent upon the change in balance of the bridge for controlling the connection of the converting device to the circuits.

6. In an electrical system, the combination with an alternating-current supply circuit, a direct-current trolley circuit and a rotary converter, of means dependent upon the resistance of the direct-current circuit for controlling the operation of the rotary converter.

7. In an electrical system, the combination with an alternating-current supply circuit, a direct-current trolley circuit and a rotary converter, of means dependent upon the change in impedance across a portion of the trolley circuit for controlling the operation of the rotary converter.

8. In a railway system, the combination with an alternating-current source of energy, a direct-current trolley circuit, a plurality of converting devices and means for connecting the converting devices between the source of energy and the trolley circuit, of means for subdividing the trolley circuit into a plurality of sections to be energized by predetermined converting devices and means co-operating with the subdividing means for controlling the connection of predetermined converting devices between the source and the trolley circuit.

9. In an electrical system, the combination with a source of energy and a continuous trolley circuit, of means for superimposing an alternating electromotive force thereon, means responsive to the change in impedance in the trolley circuit to the alternating electromotive force for controlling the source of energy.

10. In an electrical system, the combination with a source of energy and a trolley circuit, of a Wheatstone bridge device, one arm of which is the impedance in portions of the trolley circuit, and means actuated by the balancing of the bridge for controlling the source of energy.

11. In a railway system, the combination with an alternating-current source of energy, a direct-current trolley circuit, a plurality of converting devices and means for connecting the converting devices between the source of energy and the trolley circuit, of means for subdividing the trolley circuit into a plurality of sections to be energized by predetermined converting devices and means co-operating with the trolley-circuit-subdividing means for permitting the connection of an associated converting device.

- to the corresponding trolley-circuit section, while a vehicle is within the section zone limited by the circuit subdividing means, and for effecting the disconnection of the converting device after the vehicle passes out of the zone to a point beyond either of the subdividing means.
12. The combination with a direct-current load circuit and a supply circuit therefor, of means for superimposing an alternating electromotive force on the load circuit and for controlling the supply of energy from the supply circuit to the load circuit in accordance with predetermined conditions in the load circuit as indicated by a current caused to traverse the load circuit.
13. The combination with a direct-current load circuit and a supply circuit therefor, of means for superimposing an alternating electromotive force on the load circuit and for controlling the supply of energy from the supply circuit to the load circuit in accordance with the variation of the impedance of the load circuit.
14. The combination with a direct-current load circuit and a supply circuit therefor, of means for superimposing an alternating electromotive force on the load circuit and for controlling the supply of energy from the supply circuit to the load circuit in accordance with the value of the impedance of the load circuit.
15. The combination with a direct-current load circuit and a supply circuit therefor, of means for superimposing an alternating electromotive force on the load circuit and responsive to the impedance of the load circuit to the superimposed electromotive force for controlling the transfer of energy between the two circuits.
16. The combination with a direct-current load circuit and a supply circuit therefor, of means for superimposing an alternating electromotive force on the load circuit and means responsive to the impedance of the load circuit for controlling the supply of energy to the load circuit.
17. The combination with a direct-current load circuit and a supply circuit therefor, of means for superimposing an alternating electromotive force on the load circuit, means responsive to the impedance of the load circuit and means controlled thereby for controlling the supply of energy to the load circuit.
18. The method of controlling the connection of a converting device between an alternating source of energy and a direct-current trolley circuit when a vehicle enters a zone served by a predetermined section of the trolley circuit, which consists in subdividing the trolley circuit into sections by means of a plurality of reactors and then controlling the connection of a converting device to an associated section in accordance with the variation in the value of the impedance of a section caused by the entrance of a vehicle into, and the exit of the vehicle out of, the said section.
19. The method of controlling the connection of a converting device between an alternating source of energy and a direct-current trolley circuit when a vehicle enters a zone served by a predetermined section of the trolley circuit, which consists in subdividing the trolley circuit into sections by means of a plurality of reactors and then controlling the connection of a converting device to an associated section in accordance with the variation in the value of the impedance of the trolley circuit by the entrance of a vehicle into the said section.
20. The combination with a load circuit and a supply circuit therefor, of means for superimposing an alternating electromotive force on the load circuit and normally inoperative means rendered operative when the impedance of the circuit attains a predetermined value for controlling the supply of energy to the load circuit.
21. The combination with a load circuit having an electromotive force of one periodicity and a supply circuit having an electromotive force of another periodicity, of means for superimposing on the load circuit an electromotive force having a periodicity other than that of the load circuit and means responsive to the impedance of the load circuit to the superimposed electromotive force for controlling the supply of energy to the load circuit.
22. The combination with a load circuit traversed by current of one periodicity and a supply circuit therefor, of means for impressing an electromotive force upon the load circuit having a periodicity other than that of the load circuit and for controlling the load circuit in accordance with the impedance thereof to the superimposed electromotive force.
23. The combination with a load circuit traversed by current of one periodicity and a supply circuit therefor, of means for impressing an electromotive force upon the load circuit having a periodicity other than that of the load circuit and means responsive to the impedance of the load circuit to the superimposed electromotive force for controlling the energy translated between the supply and the load circuit.
24. In an electrical system of distribution, the combination with a load circuit and a source of energy therefor, of an auxiliary source, means for impressing a potential therefrom upon the load circuit and means responsive to the impedance of the load circuit including the connected load for controlling the connection of the load circuit to the source of energy therefor.

25. In an electrical system of distribution in which a load circuit is connected to a main source of electrical supply, the method of controlling the load circuit which consists in impressing upon the circuit a potential from an auxiliary source and thereby causing a current to flow through the circuit including the connected load which varies with the impedance of the load circuit and then controlling the connection of the circuit to the main source in response to the effect produced by the current.

26. In an electrical system of distribution, the combination with a load circuit, a source of energy therefor and connecting means therebetween, of means for impressing potential upon the load circuit, means responsive to an effect of the current caused to traverse the load circuit including the connected load by reason of said impressed potential, and means controlled thereby for controlling the actuation of the connecting means.

27. In an electrical system of distribution, the combination with a load circuit, a source of energy therefor and connecting means therebetween, of means for impressing potential upon the load circuit while the connecting means is ineffective, to cause current to traverse the circuit including the connected load which shall vary with the impedance of the load circuit, and means operative in response to said current for controlling the actuation of the connecting means.

28. The combination with a load circuit, a supply circuit therefor and connecting means therebetween, of means for superimposing an alternating electromotive force upon the load circuit and for controlling the supply of energy thereto from the supply circuit in accordance with a predetermined value of impedance in the load circuit including the connected load.

29. The combination with a load circuit, a supply circuit therefor and connecting means therebetween, of means for superimposing an alternating electromotive force upon the load circuit and for operating the connecting means to connect the load circuit to the supply circuit when the impedance of the load circuit including the connected load attains a predetermined value.

30. In an electrical system of distribution, a plurality of stations, energy-translating apparatus disposed at said stations, power-transmission circuit conductors between said stations, means for connecting the translating apparatus to the power-transmission conductors to permit the apparatus to transmit energy thereto, means for impressing upon the transmission circuit conductors an electromotive force having characteristics differing from the characteristics of the

power current or voltage normally traversing the circuit and means responsive to an effect of such impressed electromotive force for controlling the connection of one of the translating apparatus to the transmission circuit conductors.

31. In an electrical system of distribution, a plurality of auxiliary or sub-stations at which energy translating apparatus are disposed, a common power transmission circuit to which the respective apparatus are to supply energy, means for connecting the respective apparatus to the power transmission circuit, means for impressing upon the common circuit an electromotive force having characteristics differing from the characteristics of the normal operating potential of the power circuit, and means associated with the respective translating apparatus and responsive to an effect of the impressed electromotive force for selectively controlling the translation of energy from the associated apparatus to the power circuit.

32. In an electrical system of distribution, a plurality of auxiliary or sub-stations at which energy translating apparatus are disposed, a common power transmission circuit to which the respective apparatus are to supply energy, means for connecting the respective apparatus to the power transmission circuit, means for impressing upon the common circuit an electromotive force having characteristics differing from the characteristics of the normal operating potential of the power circuit, a source of energy for the respective apparatus, and means responsive to an effect of the impressed electromotive force for selectively controlling the translation of energy from an associated apparatus to the power circuit by controlling the energy supplied to the apparatus.

33. In an electrical system of distribution, a plurality of auxiliary or sub-stations at which energy translating apparatus are disposed, a common power transmission circuit to which the respective apparatus are to supply energy, means for connecting the respective apparatus to the power transmission circuit, means for impressing upon the common circuit an electromotive force having characteristics differing from the characteristics of the normal operating potential of the power circuit, and means associated with the respective translating apparatus selectively responsive to the effects of the impressed electromotive force for controlling the translation of energy to the power circuit from the associated apparatus.

34. In an electrical system of distribution, a plurality of auxiliary or sub-stations at which energy translating apparatus are disposed, a common power transmission circuit to which the respective apparatus are to supply energy, means for connecting the respective apparatus to the power transmission

sion circuit, means for impressing upon the power circuit an electromotive force and means associated with the respective translating apparatus and selectively responsive to an effect of the impressed electromotive force for controlling the translation of energy to the power circuit from the associated apparatus.

35. In an electrical system of distribution, 10 a plurality of auxiliary or sub-stations at which energy translating apparatus are disposed, a common power transmission circuit to which the respective apparatus are to supply energy, means for connecting the respective apparatus to the power transmission circuit, means for impressing upon the common circuit an electromotive force having characteristics differing from the characteristics of the normal operating potential 15 of the power circuit, means for connecting the apparatus to the power circuit, a source of energy for each translating apparatus, means for controlling the supply of energy to the associated apparatus and means responsive to an effect of the impressed electromotive force for controlling the supply of energy to the translating apparatus.

36. An automatically reclosing circuit-controlling device comprising means for controlling the interchange of energy in an electrical system and means comprising a Wheatstone bridge connected to the system for controlling said controlling means.

37. An automatically actuatable circuit-controlling device comprising means for permitting the transfer of energy from one portion of a system to another portion thereof and means for controlling the transferring means comprising a Wheatstone bridge, 40 one arm of which includes one portion of the system.

38. An automatically actuatable circuit-controlling device comprising means for transferring energy from one portion of a system to another portion thereof, means 45

whereby one portion of the system is connected to a network of resistors to constitute a Wheatstone bridge and means responsive to a predetermined balance therein for controlling the transferring means.

39. An automatically reclosing circuit-controlling device comprising an operating coil, an electric power system, a switch in said system controlled by said operating coil, a plurality of resistors composed into a network connected to the power system for producing a plurality of potential gradients and means responsive to the potential difference between predetermined points of the network for controlling the energization of the operating coil to control the operation of the switch.

40. An automatically reclosing circuit-controlling device comprising an operating coil, an electric power system, a switch in said system controlled by said operating coil, and a plurality of resistors composed into a network connected to the power system for producing a plurality of potential gradients, the operating coil being energized to control the operation of the switch when a predetermined potential difference obtains between predetermined points of the network.

41. An automatically reclosing circuit-controlling device comprising an operating coil, an electric power system, a switch in said system controlled by said operating coil, a plurality of resistors composed into a network connected to the power system to constitute a plurality of circuits and means for energizing the operating coil to control the operation of the switch when a predetermined potential difference obtains between predetermined points of the network.

In testimony whereof, we have hereunto subscribed our names this 26th day of June, 1918.

CHARLES McL. MOSS.
ROY J. WENSLEY.
